DESIGN FOR A CONDIMENT HOLDING DISH OR SIMILAR ARTICLE

Angelo A. Therrios, Jersey City, N. J.

Application August 10, 1940, Serial No. 94,352

Term of patent 3½ years

To all whom it may concern:

Be it known that I, Angelo A. Therrios, a citizen of the United States of America, residing at Jersey City, in the county of Hudson, in the State of New Jersey, have invented a new, original, and ornamental Design for a Condiment Holding Dish or Similar Article, of which the following is a specification, reference being had to the accompanying drawing, forming a part thereof.

I claim:

The ornamental design for a condiment holding dish or similar article, substantially as shown.

ANGELO A. THERRIOS.
